(57) **CLAIM**

The ornamental design for a folding humidifier, as shown and described.

DESCRIPTION

FIG. 1 is a top perspective view of a folding humidifier showing my new design;

FIG. 2 is another top perspective view thereof;

FIG. 3 is a bottom perspective view thereof;

FIG. 4 is a front elevational view thereof;

FIG. 5 is a rear elevational view thereof;

FIG. 6 is a left side elevational view thereof;

FIG. 7 is a right side elevational view thereof;

FIG. 8 is a top plan view thereof;

FIG. 9 is a bottom plan view thereof;

FIG. 10 is a bottom perspective view where a seal cap is in an open state; and,

FIG. 11 is a top perspective view where the folding humidifier is fully folded.

The broken lines in the drawings depict portions of the folding humidifier that form no part of the claimed design.
